HAIR CLIPPER BLADE HOLDER

Anthony Rulli, 1601 N. Wilbur St., South Bend, Ind.

Continuation of design application Ser. No. 70,589, June 18, 1962. This application Feb. 5, 1964, Ser. No.
78,532

Term of patent 14 years

(Cl. D86—10)

FIG. 2

FIG. 1

FIG. 3

FIG. 4

FIG. 5

This is a continuation of my copending application Serial No. D. 70,589, filed June 18, 1962, and now abandoned.

I claim:

The ornamental design for a hair clipper blade holder, substantially as shown and described.
